CLAIM

We claim the ornamental design for a modular socket panel, as shown and described.

DESCRIPTION

FIG. 1 is a bottom view of a modular socket panel.
FIG. 2 is a top view of the modular socket panel shown in FIG. 1.
FIG. 3 is a front view of the modular socket panel shown in FIG. 1.
FIG. 4 is a rear view of the modular socket panel shown in FIG. 1.
FIG. 5 is a left view of the modular socket panel shown in FIG. 1.
FIG. 6 is a right view of the modular socket panel shown in FIG. 1.
FIG. 7 is a first perspective view showing details of the top and front views of the modular socket panel shown in FIGS. 2-3.
FIG. 8 is a second perspective view showing details of the top, right and rear views of the modular socket panel shown in FIGS. 2, 4 and 6; and,
FIG. 9 is a third perspective view showing details of the bottom, right and rear views of the modular socket panel shown in FIGS. 1, 4 and 6.
The broken lines in the drawings illustrate portions of the modular socket panel that form no part of the claimed design.
